SAFETY RAZOR

John D. Garretson, Oakland, Calif.

Application May 2, 1933, Serial No. 668,942
Renewed June 25, 1934

11 Claims. (Cl. 30—61)

This invention relates to a safety razor consisting of a guard member, and a blade backing member, and a thin flexible blade to be clamped between the guard and backing members to retain the cutting edges of the blade in relation to openings in the opposite edges of the guard, the blade backing member being hinged to assume a folded position at times to permit the installation or removal of the blade.

10 An object of the invention is to provide a safety razor on which the blade may be conveniently mounted and relative to which the blade can be either installed or removed without the necessity of taking apart the safety razor, and the subsequent liability of loss of parts.

20 A further object of the invention is to provide a safety razor of the type mentioned, which permits of quick mounting and dismounting of the blade, and wherein the blade backing member is foldable to pass through an elongated slot in the blade, said blade being of the slotted type for cooperation with a safety razor of the character specified, the assembly being superior in point of 25 simplicity, inexpensiveness of construction, positiveness of operation, and facility and convenience in use and general efficiency.

25 In this specification and the annexed drawing, the invention is illustrated in the form considered to be the best, but it is to be understood 30 that the invention is not limited to such form, because it may be embodied in other forms; and it is also to be understood that in and by the 35 claims following the description, it is desired to cover the invention in whatsoever form it may be embodied.

In the accompanying drawing:

35 Fig. 1 represents a vertical cross section through a razor constructed in accordance with my invention, and showing the blade backing member in elevated position.

40 Fig. 2 is a vertical cross section similar to Fig. 1 but showing the blade and blade backing member in position on the guard in readiness for a shaving operation.

45 Fig. 3 is a cross section taken through Fig. 2 on the line 3—3.

Fig. 4 is a plan elevation of the razor in readiness for shaving operation.

Fig. 5 is a plan view of the razor blade.

50 In the drawing the numeral 1 indicates a guard member provided with a slot 2 along each of its opposite longitudinal edges. The upper center surface of the guard 1 is flattened as at 3, and the sides of the guard adjacent the flattened portion, are curved downwardly and outwardly as

at 4 at a proper angle for contacting the razor with the face during the shaving operation.

On each of the upper ends of the guard, on the longitudinal center thereof, are provided the blade positioning studs 5, the opposite upper surfaces of each stud 5 being curved or beveled for the purpose of giving a cam action, as will be hereinafter brought out. The studs 5 are substantially rectangular in cross section.

The guard member is mounted on a hollow 10 handle 6, which is secured to the center of the guard on the underside thereof. A spindle 7 is slidably confined in the tubular handle 6. The lower end of the handle 6 is shouldered and threaded to receive a head 8, said head being rotatable around the lower end of the handle 6. The lower end of the spindle 7 throughout a portion of the length thereof, is provided with a threaded portion 9 with which a pin 10 on the rotatable head engages, whereby rotation of the 20 head 8 and the pin 10 thru the engagement thereof with the threaded portion on the spindle 7, will cause said spindle to move axially in the handle 6.

The upper end of the spindle 7 is provided with a reduced extension 12 of rectangular cross section, the difference in cross section of the spindle 7 and the extension 12, providing a pair of shoulders 13. The extension 12 on the spindle 7 extends thru an opening 14 in the center of the 30 guard member 1. The upper end of the extension 12 is provided with a head 15 thereon, within which a laterally extended shaft 16 is confined. A blade backing member consisting of a pair of like halves 17, is swingably mounted on opposite 35 ends of the shaft 16, whereby the blade backing member may be placed in the collapsed position shown in Fig. 1, or swung into extended position shown in Fig. 2. The opposite longitudinal edges 18 of the blade backing member form surfaces to 40 engage opposite sides of the blade adjacent the cutting edges thereof. Opposite ends of the blade backing members 17 are recessed to receive and accommodate the blade positioning studs 5.

The underside of each of the halves of the blade 45 backing member is provided with a bearing 19 thereon, each bearing having a pin 20 confined therein. A bar 21 has its upper end journaled on or pivotally connected to each of the pins 20 on opposite sides of the extension 12. Each bar 21 50 extends or depends through the opening 14 in the guard member, and the lower end of each bar 21 is bent at right angles to form an outstanding flange 22, which flange has a half circle contour, to snugly engage the inner circumference of the 55

handle 6. The flanges 22 are adapted to rest on top of the shoulders or stops 13 provided on the spindle 7.

When the head 8 on the handle 6 is rotated from the position shown in Fig. 2, the spindle 7 is advanced axially in the handle to raise the blade backing member from the extended position shown in Fig. 2 into the collapsed and elevated position shown in Fig. 1. The blade backing member is held in the extended position shown in Fig. 2 by turning the head 8 on the handle to exert a downward pull on the center portion of the opposite halves of the blade backing member, which prevents said blade backing member from buckling. When the blade backing member is in the elevated position shown in Fig. 1, the shoulders 13 on the spindle 7, force the opposite flanges on the bars connected to the halves of the blade backing member into engagement with the under surface of the guard member and thus prevent the opposite halves of the blade backing member from swinging to one side or the other. If the opposite halves of the blade backing member were merely hinged to the extension on the spindle, then said halves would be free to swing in either direction. By providing the bars in pivotal connection with each of the opposite halves of the blade backing member on the under side thereof, said halves of the blade backing member are positively prevented from swinging when the said blade backing member is in the elevated position.

Whenever the blade backing member is lowered from the elevated position shown in Fig. 1 into the position shown in Fig. 2, the upper surfaces of the stops 5 act to swing the edges of the opposite halves of the blade backing member into the extended position. The length of the spindle extension 12, as well as the length of the bars 21, is such as to permit the blade backing member to be moved away from the guard 1 and to substantially clear the blade backing member from the studs 5.

The blade 25 to be mounted upon the razor above described, is of the thin, flexible type, having the cutting edges on each of the opposite longer sides thereof, and is provided with a central longitudinal aperture 26 which is in the form of a central longitudinal slot. The length of the slot is greater than the distance between the outer ends of the opposite studs 5 on the guard 1 and is greater than the length of the backing member, whereby when the blade is dropped over the backing member in the collapsed position shown in Fig. 1, and onto the studs 5, the blade cannot move lengthwise in either direction.

The slot 26 is provided with enlargements 27 at each of its opposite ends, which enlargements are adapted to engage the studs 5 and prevent sidewise movement of the blade 25. The width of the slot 26 is slightly greater than the overall thickness of the opposite halves of the blade backing member when in the folded or collapsed position shown in Fig. 1, whereby the said blade will pass freely over the collapsed halves when either placing the blade on or removing it from the razor. The contour of the slot 26 and its enlargements 27 correspond to the outline or boundary of the backing member when in the collapsed position, and of the positioning studs.

If the blade is to be placed on the razor, the razor elements are first brought into the position shown in Fig. 1. The opposite ends of the blade are grasped between the fingers and the central opening 26 of the blade is first passed down over

the collapsed halves of the blade backing member, until the slot enlargements at the opposite ends of the blade pass down over the positioning studs 5. The blade would be removed from the razor by a reversal of the movement heretofore described. When the blade is properly positioned on the guard, the blade clamping member is lowered, which action automatically shifts the opposite halves thereof into the extended position shown in Fig. 2 and clamps the opposite cutting edges of the blade in shaving position along the opposite sides of the guard member.

Having thus described this invention, what I claim and desire to secure by Letters Patent is:

1. A safety razor, comprising a guard member provided with blade positioning studs on one side thereof and a tubular handle on the other side; a blade backing member hinged on its longitudinal center line to form complementary halves; a stem to move axially in said handle and having the upper end thereof pivotally connected to the opposite halves of the backing member, whereby said backing member is movable from an extended position in contact with the guard into a collapsed position above the guard, and vice versa; cam members on the blade positioning studs to move the opposite halves of the blade backing member from the collapsed and into the extended position when the blade backing member is moved toward the guard; a blade to be clamped between the guard and blade backing member and having a central longitudinal slot fitting over the blade positioning studs and being of a length and width exceeding that of the blade backing member when in the collapsed position; and coacting means on the stem and handle for relatively moving said blade backing member into and from blade clamping position on the guard.

2. A safety razor, comprising a guard member provided with blade positioning studs on one side thereof and a tubular handle on the other side; a blade backing member hinged on its longitudinal center line to form complementary halves; a stem to move axially in said handle and having the upper end thereof pivotally connected to the opposite halves of the backing member, whereby said backing member is movable from an extended position in contact with the guard into a collapsed position above the guard, and vice versa; means pivotally connected to each of the opposite halves of the blade backing member to hold said halves in collapsed position when the blade backing member is elevated above the guard; cam members on the blade positioning studs to move the opposite halves of the blade backing member from the collapsed and into the extended position when the blade backing member is moved toward the guard; a blade to be clamped between the guard and blade backing member and having a central longitudinal slot fitting over the blade positioning studs and being of a length and width exceeding that of the blade backing member when in the collapsed position; and coacting means on the stem and handle for relatively moving said blade backing member into and from blade clamping position on the guard.

3. A safety razor, comprising a guard member provided with blade positioning studs; a blade backing member consisting of complementary halves hingedly connected along one side thereof; means slidably at right angles to said guard member, the halves of said blade backing member being hingedly mounted on said slid-

able means to cause each of the longitudinal edges thereof to substantially coincide with the longitudinal edges of said guard member when in the extended position and to fold into collapsed position on opposite sides of the slideable means when in the raised position; cam means on the blade positioning studs for swinging the opposite halves of the blade backing member into extended position as the same is moved toward the guard; a blade adapted to be clamped between said guard and blade backing member having a central longitudinal slot, the ends of which fit said blade positioning studs and being of a length exceeding that of said blade backing member, the width of said slot exceeding the width of the halves of the blade backing member when in the folded position, said slot permitting the blade to be moved over the folded halves of the blade backing member and said slideable means when the latter is raised away from the guard; and means for relatively moving the said blade backing member into clamping position with the guard.

4. A safety razor, comprising a guard member provided with blade positioning studs; a blade backing member consisting of complementary halves hingedly connected along one side thereof; means slideable at right angles to said guard member, the halves of said blade backing member being hingedly mounted on said slideable means to cause each of the longitudinal edges thereof to substantially coincide with the longitudinal edges of said guard member when in the extended position and to fold into a collapsed position on opposite sides of the slideable means when in the raised position; means pivotally connected to each of the opposite halves of the blade backing member to hold the opposite halves in non-swinging folded position on opposite sides of the slideable member when the blade backing member is in the raised position; means on the blade positioning studs for swinging the opposite halves of the blade backing member into extended position as the same is moved toward the guard; a blade adapted to be clamped between said guard and blade backing member having a central longitudinal slot, the ends of which fit said blade positioning studs and being of a length exceeding that of said blade backing member, the width of said slot exceeding the width of the halves of the blade backing member when in the folded position, said slot permitting the blade to be moved over the folded halves of the blade backing member and said slideable means when the latter is raised away from the guard; and means for relatively moving the said blade backing member into clamping position with the guard.

5. A safety razor, including a guard member; a blade; and a cap to engage the blade with the guard member, said cap being divided on its central longitudinal axis into two halves hingedly connected, whereby the cap may be elevated relative to the blade and the two halves of the cap will fold down into a position at right angles to the plane of the guard.

6. A safety razor, including a guard member; a blade; and a cap to engage the blade with the guard member, said cap being divided on its central longitudinal axis into two halves hingedly connected, whereby the cap may be elevated relative to the blade and the two halves of the cap will fold down into a position at right angles to the plane of the guard; and means to hold the two halves of the cap in a non-swinging posi-

tion when the cap is in the folded elevated position.

7. A safety razor comprising a guard member provided with blade positioning studs on one side thereof and a tubular handle on the other side; a blade backing member consisting of connected foldable complementary halves; means slideable at right angles to said guard member, the halves of said blade backing member being mounted on said slideable means whereby each of the longitudinal edges thereof when in extended position lie parallel with the longitudinal edges of said guard member, and when in the raised position said halves fold up against opposite sides of said slideable means substantially at right angles to the plane of the guard member; means connected to each of the opposite halves of the blade backing member to hold the said opposite halves in non-swinging folded position on opposite sides of the slideable means when the blade backing member is in the raised position; means on the blade positioning studs for swinging the opposite halves of the blade backing member into extended position as the same is moved toward the guard; a blade adapted to be clamped between said guard member and blade backing member having a central slot fitting over said positioning studs and being of a length and width exceeding that of the blade backing member when in the folded position, said slot permitting the blade to be moved over the folded halves of the said blade backing member and said slideable means when raised away from the guard; and co-acting means on the handle and slideable means for relatively moving said blade backing member into and from blade clamping position on the guard member.

8. A safety razor comprising a cap member, a blade and a guard member; said guard member having studs upon one side thereof for positioning the blade and cap and for extending the cap member into clamping position upon the guard member; a tubular handle on said guard member; means slidably mounted in said handle upon the outer end of which is mounted the cap member; said cap member being centrally divided into halves foldable upon opposite sides of the slideable means; means to hold the cap member in a non-swinging position at an angle to the guard member for blade placement; co-acting means on the handle and slideable means for raising and lowering the cap member from and into clamping position upon the guard member; a blade adapted to be clamped and flexed between the cap member and the guard member and having a central slot fitting over the blade positioning studs and being of a width and length permitting the blade to be moved over the folded halves of the cap member and slideable means when the same are in the raised position.

9. A safety razor, including a guard member; a blade; and a cap to engage the blade with the guard member, said cap being divided on one of its major axes into two halves; and means whereby the cap may be elevated relative to the blade so that the two halves of the cap will fold down into a position at right angles to the plane of the guard.

10. A safety razor, including a guard member; a blade; and a cap to engage the blade with the guard member, said cap being divided on one of its major axes into two halves; means whereby the cap may be elevated relative to the blade so that the two halves of the cap will fold down into a position at right angles to the plane of the

guard; and means to hold the two halves of the cap in a non-swinging position when the cap is in the folded elevated position.

5 11. A safety razor including a guard member, a blade backing member and a blade; said guard member having blade positioning studs on the upper surface thereof at opposite ends thereof, the upper surface of said studs being inclined downwardly from the center thereof in opposite directions and the upper surface of said guard between said studs being flat to provide a contacting area for flexing the blade between the opposite edges of the guard member and the blade

backing member; said blade backing member being pivotally mounted on means slidable on said guard member and having opposite outer ends thereof extended for riding upon the cam surface of the blade positioning studs to swing the backing member as it is raised and lowered, and having the under surface of said blade backing member recessed for flexing the blade on the guard member; said blade member having an aperture adapted to fit over the blade positioning studs on the opposite ends of the upper face of the guard member. 10

JOHN D. GARRETSON.
